(57) **CLAIM**

The ornamental design for a beverage container cap drink spout, as shown and described.

DESCRIPTION

FIG. 1 is a front, top, left isometric view of the new design. FIG. 2 is a rear, top, right isometric view of the new design. FIG. 3 is a left side view of the new design.

FIG. 4 is a right side view of the new design.

FIG. 5 is a front view of the new design.

FIG. 6 is a rear view of the new design.

FIG. 7 is a top view of the new design.

FIG. 8 is a bottom view of a beverage container cap associated with the new design.

FIG. 9 is a front, top, left isometric view of the new design, shown together with an associated liquid container.

FIG. 10 is a rear, top, left isometric view of the new design, shown together with an associated liquid container, an associated drink spout cover, and an associated tether, with the drink spout cover in a closed position over the drink spout; and,

FIG. 11 is a rear, top, left isometric view of the new design, shown together with an associated drink spout cover and an associated tether, with the drink spout cover in a stowed position removed from the drink spout.

The dashed lines shown in the drawings illustrate portions of the drink spout (e.g., the internal structure of the drink spout) that form no part of the presently claimed design (FIGS. 1-2, and 7-11) and illustrate environmental structure of an associated beverage container cap (FIGS. 1-11), an associated liquid container (FIGS. 9-10), an associated drink spout cover (FIGS. 10-11), and an associated tether (FIGS. 10-11) that form no part of the presently claimed design.
